SCANNING CIRCUIT FOR ELECTRONIC
MULTISELECTORS HAVING MOS TRANSISTOR
MATRIX

The present invention is related to a scanning circuit which sets up electronic multiselectors for switching network in which the contacts located at the cross-points are made up of field effect transistors.

A multiselector of this type which comprises m verticals and n horizontals has been described in the case P. Girard, M. J. P. Leger, C. P. H. Lerouge, J. H. Dejean 10-4-14-17 U.S. Pat. application No. 819,700, filed Apr. 28, 1969.

It will be briefly reminded that in such a multiselector, each switching circuit located at the cross-point between two perpendicular speech conductors made up of a vertical j and a horizontal k of the multiselector comprises first, a contact element made up of a field effect transistor with insulated grid the source and the drain of which are connected respectively to the vertical j and to the horizontal k considered and second, a holding flip-flop comprising transistors of the same type the 1 output terminal of which is connected to the switching transistor grid so that, when the said flip-flop is in the 1 state, the said transistor is conducting ("low impedance on" state) which corresponds to the closing of a contact connecting the conductors j and k .

It will be observed that a cross-point may comprise several contact elements controlled by one same holding flip-flop. In case of a multiselector for switching network, the cross-point comprises four contact elements, two per speech direction.

A matrix of an elementary multiselector comprises m verticals and n horizontals to which are associated as many selection conductors. The selection of the vertical j is carried out by the application of a signal C_j to the vertical selection conductor c_j ; the selection of the horizontal k is carried out by the application of a signal $\bar{S}_k$ to the horizontal selection conductor s_k . Moreover the matrix comprises on the one hand, n busy state conductors $e_1, e_2 \dots e_k \dots e_n$ associated to the horizontals, a signal E_k appearing on the conductor e_k when at least one contact is closed on the said horizontal and on the other hand, n free horizontal conductors $e'_1, e'_2 \dots e'_k \dots e'_n$ associated to the horizontals, a signal E'_k appearing on the conductor e'_k when all the contacts of the said horizontal are open. At the rest state, signals $\bar{C}_j$ and S_k are applied to the selection inputs in such a way that the state of the holding flip-flop may not be changed; an inverter circuit to which is applied the signal C_j supplies a signal $\bar{C}'_j$ delayed by an amount of time t slightly higher than the switching time of the holding flip-flop.

The matrices of the elementary multiselectors may be manufactured in large scale integrated circuits the cost price of which is all the lower as the number of circuits manufactured is higher; therefore, it is interesting to apply this multiselector to a great number of uses.

The object of the present invention is thus to realize a scanning circuit which sets up a multiselector.

According to one feature of the present invention, an electronic scanning circuit is made up of a multiselector comprising m verticals and n horizontals in which the free horizontal conductor e'_k associated to the horizontal k is connected to the selection conductor s_{k+1} associated to the horizontal $k+1$.

The above-mentioned and other features and objects of this invention will become apparent by reference to the following description taken in conjunction with the accompanying drawings in which:

FIG. 1 illustrates the detailed diagram of a switching circuit and its associated circuits;

FIG. 2 illustrates the diagram of a scanning circuit with one single stage;

FIG. 3a to 3d illustrate the diagram of the control signals of the scanning circuit of FIG. 2;

FIG. 4 illustrates the diagram of a scanning circuit with two stages.

Before describing FIG. 1, the main features of the MOS transistors and their mode of operation will be reviewed. All the transistors shown in FIG. 1 are of this type.

A MOS transistor is almost completely symmetrical and the electrodes which operate as drain and source may be inverted without any drawback and without modifying its operation when it is used as a logical circuit. Nevertheless, the manufacturer defines, in the specifications, the electrodes which operate as source and drain. Consequently, in the figures, the source is symbolized by an arrow as the emitter of a bipolar transistor.

In the operation of a MOS-Ph transistor (type P, enhancement mode transistor) the following voltages are defined:

V_I : threshold voltage,

V_D : drain voltage,

V_G : grid voltage.

All these voltages being measured with respect to that of the source ($V_S=3$) and expressed in absolute values, a MOS transistor is in its "high impedance off" or "blocked" state when $V_G \leq VT$. It then has a drain-source resistor RDS of value practically infinite (approximately 10^7 ohms).

A MOS transistor is conducting or "on" when $V_G > VT$. It then behaves as a passive resistor of value

$$RDS = \frac{1}{K(VG - VT)} \quad (1),$$

K being a proportionality factor.

In this case, there are two "on" regions:

The "low impedance on" region (or nonsaturated region) when $V_D < VG - VT$ with a drain-source resistance RDS of low value (50 to 200 ohms).

The "high impedance off" region (or saturated region) when $V_D \geq VG - VT$ with a resistance RDS of relatively high value.

If a MOS-Ph transistor has a threshold voltage $VT = -4$ v. and if a voltage $VG = 0$ is applied to it, it becomes blocked. If a voltage $VG = -24$ v. and a voltage V_D ranging between zero and -20 volts is applied to it, it sets into the on state.

In practice if a good linearity of the resistance RDS is required, one must use the lower values of V_D . The resistance RDS of the transistor then has a very low value and it allows bidirectional transfer of analog or digital signals between drain and source.

The MOS transistors are also used as resistors, this enabling to manufacture large scale integrated circuits, this passive element operation may be obtained for both types of conduction. For instance, if the transistor operates in the low impedance on region with a suitable bias ($V_D < VG - VT$) and if it is connected in series with an inverter MOS transistor, either the voltage V_D or the ground voltage appears at the connection which is common to the two transistors according to whether the said inverter transistor is off ($VG \leq VT$) or on ($VG > VT$).

In the various figures accompanying the description, MOS transistors operating as active elements bear the reference T and those operating as load resistors bear the reference R. It is obvious that the use of MOS transistors as load resistors is only feasible when integrated technology is employed in which case they offer advantages from manufacturing point of view. However it is well understood that each MOS transistor bearing the reference R and used as resistor may be replaced by a conventional resistor of same value.

FIG. 1 illustrates the detailed diagram of a switching circuit X_{jk} located at the cross-point of the vertical V_j and of the horizontal H_k of a multiselector comprising m verticals and n horizontals. Such a circuit X_{jk} comprises the bidirectional cross-point K_{jk} , its control circuit comprises the flip-flop A_{jk} and the NOR-circuit P_{jk} . FIG. 1 illustrates also the detailed diagram of a logical circuit G_k associated to the horizontal H_k and of the delay circuit L_j associated to the vertical V_j .

This switching circuit is controlled by a certain number of signals transmitted over the conductors $c_j, c'_j, s_k, e_k, p_{jk}, a_k$. The conductor c_j is connected to the inverter circuit L_j associated to the vertical V_j and to the n flip-flops ... $A_{j1} \dots A_{jn}$ associated to the vertical V_j .

The conductor c'_j is connected to the n NOR-circuits $P_{j1} \dots P_{jn}$ associated to the vertical V_j . The conductor s_k is connected to the m NOR-circuits P_{jk} associated to the horizontal H_k . The conductor e_k , coming out of the logical cir-

cuit G_k associated to the horizontal H_k , is connected to the m NOR-circuits $P_{1k} \dots P_{jk} \dots P_{mk}$ associated to the horizontal H_k . The conductor p_{jk} , coming out of the NOR-circuit P_{jk} , is connected to the flip-flop A_{jk} .

Table I indicates the various signals applied to the control conductors as well as the corresponding voltage levels and the designation of the signals. These signals bear the same references as the conductors to which they are applied, but the first letter is a capital one. For the purpose of simplification, the references of the conductors and signals do not bear, in this table, the letters j, k identifying the horizontal and the vertical to which each cell is associated. As it can be seen from this table a signal of amplitude -2 selection conductor s_k characterizes the nonselection of the horizontal H_k .

The cross-point K_{jk} , located at the intersection of the horizontals H' , H'' and of the verticals V' , V'' , carries out the connection between the conductors $H'k-V'j$ and $H''k-V''j$ when the MOS-Ph transistors T_{12} and T_{13} are in the on state. The control signal A_{jk} applied to the grids of these transistors is supplied by the flip-flop bearing the same reference or the holding flip-flop which comprises the MOS-Ph transistors T_3 , T_4 , T_5 , T_6 , R_4 , and R_5 .

The mode of operation of such a flip-flop in which the transistors T_5 and T_6 are used to control the switching, is similar to that of a flip-flop equipped with bipolar transistors PNP and will not be described in detail.

TABLE I

Conductor	Signal	Voltage	Designation
c	$\bar{C}$	0	
	C	$-U_2$	Connection signal
c'	$\bar{C}'$	0	Delayed connection signal
	C'	$-U_2$	
s	$\bar{S}$	0	
	S	$-U_2$	Nonselection signal
e	$\bar{E}$	0	
	E	$-U_2$	Busy signal
a	$\bar{A}$	0	
	A	$-U_2$	Closing signal
p	$\bar{P}$	0	
	P	$-U_2$	Preselection signal

Table II hereunder indicates the states of the transistors T_3 and T_4 according to whether the flip-flop is in the 1 or 0 state as well as the state of the cross-point K_{jk} and the drain voltages of these transistors.

TABLE II

State of the flip-flop	State of the transistors		State of the cross-point	Voltage levels	
	T3	T4		Output I (Drain of T_3)	Output o (Drain of T_4)
1 state	Blocked	Conducting	Closed	$-U_2$	0
0 state	Conducting	Blocked	Open	0	$-U_2$

¹ Signal A_{jk} .

² Signal $\bar{A}_{jk}$.

The grids of the control transistors T_5 and T_6 are brought up either to the potential $-U_2$ (logical conditions C_j , P_{jk}) or the ground potential (logical conditions $\bar{C}_j$, $\bar{P}_{jk}$). It is seen that, for the logical condition C_j , the transistor T_5 is conducting and that the flip-flop A_{jk} is reset in the 0 state (logical condition $\bar{A}_{jk}$) and that, for the condition P_{jk} , it is set in the 1 state (logical condition A_{jk}).

It will be noted that if the transistors T_5 and T_6 are simultaneously conducting by the application of the signals C_j and

P_{jk} , the drains of the transistors T_3 and T_4 are both forced to the ground potential and the signal A_{jk} appears.

The logical circuit G_k comprises a NOR-circuit $G''k$ comprising the MOS-Ph transistors T_1 , T_2 ... T_m connected in parallel and R_6 , and an inverter circuit $G''k$ comprising the MOS-Ph transistors T_7 and R_7 . The grids of the transistors T_1 to T_m are connected respectively to the output terminals of the flip-flops A_{1k} to A_{mk} of the horizontal H_k so that the NOR-circuit $G''k$ delivers, on the conductor $e'k$, a signal $E'k$ of amplitude $-U_2$ for the logical condition $E'k = A_{1k} + A_{2k} + \dots + A_{mk}$.

This signal $E'k$ means that all the switching circuit associated to the horizontal H_k are open: it will be called hereafter "free horizontal signal." In an achievement of large scale integrate circuits, the conductor $e'k$ constitutes an output conductor of an elementary multiselector.

The inverter $G''k$ delivers a signal E_k of amplitude $-U_2$ for the logical condition $E_k = A_{1k} + A_{2k} + \dots + A_{mk}$; this signal E_k means therefore, according to table I, that at least one switching circuit associated to the horizontal H_k is closed: it will be called hereafter the "busy state signal."

The inverter circuit L_j , which comprises the MOS-Ph transistors T_8 and R_8 , is identical to the circuit $G''k$ and delivers signals $\bar{C}_j$ or C_j according to whether the signal transmitted by the vertical selection circuit c_j is C_j corresponding to the connection signal or $\bar{C}_j$. The switching time of the MOS transistor used to invert the signal has a value t and, for instance, when the connection signal is suppressed (shifting from the condition C_j to the condition $\bar{C}_j$), the signal $\bar{C}_j$ remains still during a time t .

The NOR-circuit P_{jk} which comprises the MOS-Ph transistors T_9 , T_{10} , T_{11} , R_9 is identical to the circuit $G''k$ and delivers a preselection signal p_{jk} of amplitude $-U_2$ for the logical condition: $P_{jk} = C'_j + S_k + E_k = \bar{C}'_j \bar{S}_k \bar{E}_k$. It is seen thus by referring to table I that the preselection signal P_{jk} is only present when the three following conditions are simultaneously fulfilled:

The horizontal H_k is free (condition $\bar{E}_k$),

40 The horizontal H_k is selected (condition S_k),

The delayed connection signal is present (condition $\bar{C}'_j$).

The operation of the circuit of FIG. 1 will be now described in relation with table III. This description will be divided into two parts concerning respectively the effect of the control signals on a nonselected cell and a specific process for closing the switching circuit X_{jk} located at the intersection of the vertical V_j and the horizontal H_k .

1. Nonselected cells

The lines 1.1, 1.2, 1.3 in table III indicate the signals and the voltages present over the conductors c , c' , s , e , and p (output terminal of NOR-circuit P_{jk} , FIG. 1) in the following cases.

1.1 Rest state (table III, reference 1.1)

In the rest state, i.e., when neither the closing nor the opening K_{jk} are controlled, signals $\bar{C}_j$ and S_k are applied to the selection inputs as well as one of the signals $\bar{E}_k$ or E_k . The signal $\bar{C}_j$ blocks the control transistor T_5 of the flip-flop A_{jk} and the signals S_k and C'_j block the gate P_{jk} so that the state of the flip-flop is held in position whatever the level of the voltage over the conductor e_k may be.

60 It will be pointed out that if a signal $\bar{S}_k$ is applied when the transistor T_5 has been receiving a signal $\bar{C}_j$ for at least a time t , the signal C'_j still blocks the gate P_{jk} .

1.2 Application of a connection signal (table III, reference 1.2)

The application of a signal C_j to the vertical selection conductor c_j initiates the opening of all the cross-points associated to the vertical V_j . In effect, this signal makes all the transistors T_5 conducting and the flip-flops A are reset in the 0 state. the 70 line 1.2 of table III represents the various voltages in the case of nonselected horizontals (signal S).

1.3 Application of a selection signal (table III, reference 1.3)

When the horizontal H_k is selected by the application of a signal $\bar{S}_k$, the nonselected verticals receive a signal $\bar{C}$ and it

can be seen that each gate P remains blocked provided that the signal C should be applied for at least a time t before the application of the signal $\bar{S}k$.

TABLE III

Ref.	Operation	Conductors				Flip-flop A
		c	c'	s	e	
1.1	Rest	$\bar{C}j(0)$	$C'j(-U2)$	$S_k(-U2)$	$\bar{E}k$ ou E_k	$\bar{P}jk$

2. Closing of a cross-point

By way of nonlimitative example, a process for closing the circuit Xjk will be now described by assuming that initially the voltages applied are those corresponding to the rest state (table III, reference 1.1) and that the horizontal Hk is free, i.e., that a signal $\bar{E}k$ is present over the conductor ek . This closing process comprises the following operations carried out in time succession:

2.1 Horizontal selection (table III, reference 2.1)

A signal $\bar{S}k$ is applied to the conductor sk . As a signal $C'j$ is present, the gate Pjk is blocked and the flip-flop Ajk does not switch.

2.2 Vertical selection

A signal Cj is applied to the conductor so that the flip-flop Ajk is reset in the 0 state (condition Ajk). After a delay t , the circuit Lj delivers a signal $\bar{C}j$ and, if the horizontal is free, this being characterized by a signal $\bar{E}k$, a signal Pjk appears so that the drains of the transistor $T3$ and $T4$ are both grounded (table III, reference 2.2). The transistors $T12$ and $T13$ (FIG. 4) are blocked and the cross-point is still open (condition Ajk).

2.3 Closing of the cross-point

The signal Cj is suppressed (condition $\bar{C}j$) but the signal $\bar{C}j$ is still present during a time t . The transistor $T3$ is therefore blocked whereas the transistor $T4$ remains conducting under the control of the signal Pjk (table III, reference 2.3a).

Consequently the flip-flop Ajk is set in the 1 state (condition Ajk) making the transistors $T12$, $T13$ conducting: the cross-point is closed and a signal E_k appears which blocks the gate Pjk (signal $\bar{P}jk$). After a time t , it appears also a signal $C'j$ (table III, reference 2.3b): the cross-point is held in the closed position.

2.4 End of operation

The signal $\bar{S}k$ is suppressed (condition S_k) and the device is in the rest position (table III, reference 1.1).

FIG. 2 illustrates a multiselector with m verticals and n horizontals which allows to connect a circuit 1 comprising n output conductors to a circuit 2 comprising m input conductors. The n output conductors of the circuit 1 are connected to the horizontals $H1$ to Hn and the m output conductors of the circuit 2 are connected to the verticals $V1$ to Vm . On this FIG. 2, one has shown the various switching circuits Xjk of FIG. 1 by squares from which go out conductors cj , $c'j$, sk , ak previously defined. One has also represented the various circuits Gk to which are connected the m conductors ak of a horizontal. As it has been seen previously, this circuit Gk comprises a NOR-circuit $G'k$ the output conductor of which $e'k$ is, in the case of a multiselector for switching network, connected to an output terminal of the multiselector. A signal $E'k$ of amplitude $-U2$ appears for the logical condition $E'k = A1k + A2k + \dots + Amk$, thus meaning that all the cross-points of the horizontal k are open. According to the present invention, the conductor $e'k$ is connected to the conductor $sk+1$ of the following horizontal. Thus, $e'1$ is connected to $s2$, $e'2$ to $s3 \dots e'n-1$ to sn ; the first conductor $s1$ is connected to the flip-flop 3 identical to the flip-flop Ajk of the FIG. 1, i.e., to the drain of the transistor $T3$.

The conductors cj are connected to the circuit 4 which

delivers signals Cj defined by the diagrams of the FIGS. 3b to 3d; these signals are constituted by negative pulses of amplitude $U2$ obtained by division by m of the clock H of the dia-

gram of the FIG. 3a.

The signal $C1$ is also applied to the flip-flop 3 (grid of the transistor $T5$) through an AND circuit open by a signal ST the duration of which is equal to m periods T of the clock signal H if it is required to carry out one single scanning cycle of the outputs of the circuit 1. The flip-flop 3 receives also the signal $C2$ applied to the grid of the transistor $T6$.

The mode of operation of this scanning circuit is the following assuming that at the beginning all the cross-points are open. When the signal ST is applied to the AND-circuit 5, the first pulse of the signal $\bar{C}1$ resets the flip-flop 3 to the 0 state so that the conductor $s1$ receives a signal $\bar{S}1$. The conductor $c1$ receives also a signal $C1$ and when it disappears, the cross-point $K11$ closes and connects the horizontal $H1$ to the vertical $V1$. A busy state signal $E'1$ appears over the conductor $e'1$ and is applied to the selection conductor $s2$. This signal $E'1$ corresponds to a selection signal of the horizontal $H2$ so that when the first pulse of the signal $C2$, applied to the connection conductor $c2$, disappears, the cross-point $K22$ closes. The signal $C2$ is also applied to the flip-flop 3 to set in the 1 state and it delivers then a voltage level $-U2$ which corresponds to a nonselection signal.

The cross-points $K33$, $K44 \dots Kmm$ are thus closed by turns during the occurrence of each first pulse of the signals $C3$, $C4 \dots Cm$. The pulse following the first pulse of the signal Cm is the second pulse of the signal $C1$ which opens all the cross-points of the vertical $V1$ (table III, reference 1.2) and in particular the cross-point $K11$. When this second pulse of the signal $C1$ disappears, the cross-point $K1m+1$ closes and the NOR-circuit $G'1$ delivers a signal $E'1$ which, applied to the conductor $s2$, corresponds to a nonselection signal. Thus, when the second pulse of the signal $C2$ is applied to the conductor $C2$, the cross-point $K22$ opens whereas the cross-point $K2m+2$ closes. There are then m cross-points closed simultaneously thus allowing to connect m of the n outputs of the circuit 1 to the m outputs of the circuit 2.

When the cross-point Kmn closes, the NOR-circuit $G'n$ delivers a signal $\bar{E}'n$ over the conductor $e'n$; if this conductor $e'n$ is connected to the selection closed conductor $s1$, the following pulse of the signal $C1$ opens the cross-point closed by the preceding pulse of the signal $C1$ and closes the cross-point $K11$: a new scanning cycle thus begins. If the conductor $e'n$ is not connected to the selection conductor $s1$, the m cross-points of the m last horizontals open if one keeps on applying the signals $C1$ to Cm to the connection conductors; a new scanning cycle can take place only if the signal ST appears.

The operation of the circuit of FIG. 2 shows the existence of m simultaneous links between the circuits 1 and 2, these m links corresponding to m successive outputs among the n of the circuit 1. One may thus consider the circuit of FIG. 2 as the equivalent of m scanning circuits of conventional type operating in parallel.

The invention has been described in the case of a scanning circuit comprising a multiselector of n horizontals and m verticals, however it is understood that a multiselector may be achieved by the grouping of several elementary multiselectors comprising for instance each one two horizontals and four ver-

ticals. By grouping such elementary multiselectors, one may, or instance, obtain a multiselector with 256 horizontals and four verticals; each vertical is thus connected to 256 horizontals, this introducing a problem of parasitic capacity. In order to avoid this drawback, it is proposed to achieve the scanning circuit in two stages as shown on FIG. 4. The first stage comprises eight multiselectors M1 to M8 each one comprising 32 horizontals and four verticals. The horizontals, shown in thin line, are connected to the 256 outputs of the circuit 1. The four verticals, also represented in thin line, are connected to the horizontals of the multiselector M' constituting the second stage; this multiselector is identical to the preceding ones and its four verticals are connected to the circuit 2.

The control conductors of the various multiselectors have been represented in thick line. Thus, in each multiselector, one has shown the conductor e' of each horizontal which is connected to the selection conductors of the following horizontal. However, this connection is interrupted every four horizontals and the corresponding selection conductor is connected to one of the output conductor A1 to A8 of the decoding circuit D1, in the case of the multiselectors M1 to M8, and to one of the output conductors B1 to B8 of the decoding circuit D2, in the case of the multiselector M'. The decoding circuit D2 is associated to a counter Cp2 receiving the pulses from the signal C1 of the FIG. 3b; the decoding circuit D1 is also associated to a counter Cp1 receiving the pulses from a signal K' obtained by division by eight of the pulses of the signal C1. The output conductors of the decoding circuit D1 and D2 can be activated only if they receive a signal ST. When an output conductor of a decoding circuit is activated, it supplies a voltage level equal to the ground. The connection conductors c1 to c4 of the multiselector M' are connected to a circuit 8 which delivers the signals C1 to C4 and K'. In the absence of the signal ST, this circuit does not supply any signal.

The operation of the circuit is the following assuming that all the cross-points of the multiselectors are opened and that the code displayed by the counters Cp1 and Cp2 corresponds to the activation respectively of the wires A8 and B8. The first pulses which appear after the signal ST are a pulse of the signal C1 and a pulse of the signal K'. The pulse of the signal C1 activates, on the one hand, the connection conductor c1 of the multiselector M' and, on the other hand, the selection conductor S'1 through the counter Cp2 and the decoder D2. Therefore, the first cross-point of the first horizontal closes; the signal E'1 is applied, on the one hand, to the selection conductor s'2 of the second horizontal and, on the other hand, to the connection conductor c1 of the multiselector M1. This conductor c1 was previously at the voltage level $-U_2$ which corresponded to a connection signal; at the same time, the selection signal is applied to the conductor s1 through the conductor A1 of the decoder D1; thus, when the condition E'1 appears, the cross-point of the horizontal H1 closes. The two closed cross-points of the multiselectors M1 and M' allow to connect the horizontal J1 to the vertical V1 and to have a link between the circuits 1 and 2.

The pulse of the signal C2 (FIG. 3c) is applied to the conductor c2 of the multiselector M' and closes in a first stage the cross-point corresponding to the second horizontal, then in a second stage the cross-point of the second horizontal of the multiselector M1. The four cross-points of the first four horizontals of the multiselectors M' and M1 close thus by turns so that after the pulse of the signal C4, four links exist between the circuits 1 and 2.

The pulse of the signal C1 which appears afterwards opens the cross-point of the first horizontal of the multiselector M' and steps it up by one position the counter Cp2 so that the conductor B2, connected to the selection conductor s'5 is activated. The closing of the cross-point gives rise to a signal E'1 which opens the cross-point of the horizontal H1 of the multiselector M1. When the pulse of the signal C1 disappears, the cross-point of the fifth horizontal of the multiselector M' closes, which initiates the closing of the cross-point of the horizontal H33 of the multiselector M2.

The cross-points of the horizontals H33 to H36 of the mul-

tiselector M2 close thus by turns whereas the homologous cross-points of the horizontal H1 to H4 for the multiselector M1 open. These simultaneous closings and openings of the cross-points of the first four horizontals of the multiselectors M1 to M8 take place by turns at the rate of the pulses of the signals C1 to C4 applied to the connection conductors of the multiselector M'.

The ninth pulse of the signal C1 activates the conductor B1 of the decoding circuit D2, and at the same time, the second pulse of the signal K' activates the conductor A2 of the decoding circuit D1. Therefore, the closing and opening operations will be carried out by turns on the horizontals 5 to 8 of the multiselectors M1 to M8.

When the signal ST disappears, the selection conductors no longer receive signals and the four closed cross-points open at the rate of the pulses of the signals C1 to C4.

While the principles of the above invention have been described in connection with specific embodiments and particular modifications thereof, it is to be clearly understood that this description is made by way of example and not as a limitation of the scope of the invention.

In particular, opposite polarity transistors may be used by inverting the polarities of the power supply sources.

We claim:

1. An electronic scanning circuit for setting up electronic multiselectors comprising
  - a matrix of m verticals and n horizontals to which are associated vertical and horizontal selection conductors c_j and s_k ,
  - means for selecting a vertical j by applying a connection signal C_j over the associated vertical conductor c_j , and
  - means for selecting a horizontal k by applying a horizontal connection signal $\bar{S}_k$ over the conductor s_k ,
  - a plurality of switching circuits, coupled at the juncture of said vertical and horizontal selection conductors,
  - each circuit including a contact element formed by a MOS transistor,
  - each transistor including grid and source and drain electrodes,
  - means coupling said source and drain electrodes across said conductors to be coupled,
  - a holding flip-flop formed by MOS transistors as part of each switching circuit,
  - means connecting the 1 output of each flip-flop to the grid of the associated transistor which serves as the contact element, whereby the transistor conductors when the flip-flop is in the 1 state and is blocked when the flip-flop is in the 0 state, and
  - a logic circuit coupled to respond to the condition of a plurality of the flip-flops to provide a free horizontal signal when the flip-flops are in their 0 state indicating all the horizontal circuits are open, and
  - means coupling the free horizontal signal to the selection conductor s_{k+1} in the horizontal $k+1$.
2. An electronic scanning circuit as claimed in claim 1, in which
  - means are provided to reset the flip-flop to the 0 state by the application of a connection signal C on its 0 output, and
  - means are provided for setting the flip-flop to its 1 state by the application of a signal P from an electronic gate, said electronic gate in turn providing the signal P in response to simultaneous receipt of a signal C', a selection signal $\bar{S}$ and a signal $\bar{E}$.
3. An electronic scanning circuit as claimed in claim 1, in which the matrix comprises
  - m delay conductors associated with the verticals,
  - the delay conductors producing a signal $\bar{C}'_j$ delayed by an amount of time t relative to the signal C_j appearing on the conductor c'_j associated with the vertical j ,
  - n busy state conductors associated with the horizontals,
  - the busy state conductors carrying a signal E_k on the conductor e_k associated with the horizontal k when one of the switching circuits is closed on the said horizontal, and
  - n free horizontal conductors associated with the horizon-

tals;

4. An electronic scanning circuit as claimed in claim 1, in

which

a free horizontal conductor $e'k$ associated with the horizontal k is connected to a selection conductor $sk+1$ of the horizontal $k+1$. 5

5. An electronic scanning circuit as claimed in claim 1, in

which

identical series of pulses shifted with respect to time are supplied to the selection conductors associated with the 10

6. An electronic scanning circuit as claimed in claim 1, in

which

the selection conductor associated with the first horizontal receives, at the beginning of each scanning cycle, a selection signal $\bar{S}1$.

7. An electronic scanning circuit as claimed in claim 1, in

which

a free horizontal conductor $e'n$, associated with the last horizontal n , is connected to the selection conductor associated with the first horizontal.
